CIGARETTE DISPENSER

Lawrie L. Witter, Jamaica Plain, Mass.

Application January 10, 1933, Serial No. 650,991

7 Claims. (Cl. 312—84)

This invention relates to cigarette dispensers and this application is a continuation in part of my copending application Serial No. 387,656, filed August 22, 1929. The primary object of the invention is to provide a new and improved type of cigarette dispenser which is relatively simple in construction and operation, is convenient to reload, substantially houses the cigarettes from exposure to the atmosphere and dispenses them individually as needed, and which is adaptable to be constructed in a variety of ornamental and useful forms.

It is well known that cigarettes rapidly lose their flavor and become dry and frayed at the ends when exposed to the atmosphere. I am familiar with many cigarette dispensers heretofore known and all of such dispensers have been so constructed that air can pass freely thereto and therefrom and cause this deterioration of the cigarettes. One of the objects of my invention is the production of an improved cigarette dispenser which eliminates this objection. The form of the invention illustrated in the accompanying drawing embodies a channel open only at its upper and lower ends and having a magazine at the upper end supplying cigarettes thereto. The lower end is normally closed by a gate with which cooperates a selector in the channel, the arrangement being such that each time the gate opens to dispense a cigarette the selector delivers a cigarette thereto from the magazine. The production of a new and improved cigarette dispenser of this nature comprises a further object of the invention.

In another aspect, my invention resides in an improved cigarette dispenser adapted to receive and dispense cigarettes directly from the original container in which they are purchased, thus eliminating the usual handling and exposure of the cigarettes prior to their use. In this form of the invention the dispenser and container are so constructed as to adapt the former to receive and support the latter in position thereon supplying cigarettes to the channel from which they are dispensed individually as required.

Another aspect of the invention relates to its adaptation to and use in connection with smoker's cabinets, ash trays and the like, wherein the use of a cigarette dispenser is desirable. The cigarette dispenser of my invention is readily adaptable to such uses, which comprise a further object of the invention.

These and other features of the invention will be best understood and appreciated from the following description of certain embodiments thereof,

selected for purposes of illustration and shown in the accompanying drawings, in which

Fig. 1 is a front elevation of a cigarette dispenser embodying my invention;

Fig. 2 is an elevation of the right-hand end thereof;

Fig. 3 is a longitudinal section taken on line 3—3 of Fig. 2;

Fig. 4 is a cross section taken on line 4—4 of Fig. 1;

Fig. 5 is a fragmentary cross section like Fig. 4 and showing the dispensing operation;

Fig. 6 is a fragmentary cross section of a modified form of the invention;

Fig. 7 is a fragmentary elevation of a smoker's cabinet showing my invention applied thereto;

Fig. 8 is a sectional view through the cabinet on line 8—8 of Fig. 7 and showing the dispenser in end elevation;

Fig. 9 is a plan view taken on line 9—9 of Fig. 8;

Fig. 10 is a front elevation, mostly in section, of my improved cigarette dispenser with a removable magazine;

Fig. 11 is a fragmentary front elevation, similar to Fig. 10 but showing the magazine removed;

Fig. 12 is a right-hand end elevation of the dispenser, partly in section, on line 12—12 of Fig. 10;

Fig. 13 is a perspective view, partly in section, of the original cigarette container or box which is adapted to serve as the cigarette magazine in the dispenser shown in Figs. 10—12;

Fig. 14 is a fragmentary elevation illustrating the application of the dispenser to the container or box; and

Fig. 15 is a fragmentary sectional view of a slightly modified form of container and dispenser.

As has been heretofore suggested, my invention may be constructed in various ornamental and useful shapes and in various forms and may be adapted to serve in several different combinations. The form illustrated in Figs. 1—5 of the drawings embodies a cigarette dispenser as an independent unit and I will first describe this embodiment.

In Figs. 1—5, the main body member 10 of the dispenser is preferably formed in one piece, as by molding, and embodies a base portion 12, an intermediate portion providing a channel 14 and a top portion providing a magazine 16. A cover 18 for the magazine may be pivoted at 20 and is adapted to fit closely and close tightly the magazine against the passage of air. This fitting may be facilitated by recessing the inner peripheral edge of the magazine at 22 and a sealing gasket 24 of rubber may also be provided. A latch 26

serves to hold the cover in its tightly closed position.

The lower end of the magazine is normally closed by a gate 28, illustrated as pivoted at 30 and preferably recessed adjacent to its edges to fit closely and close tightly said end against the passage of air. A sealing gasket 32 may also be provided. The gate is shown in its closed position in Fig. 4 and in its open and dispensing position in Fig. 5. With the cover 18 and gate 28 in closed position, the cigarettes are so substantially housed from exposure to the atmosphere that the objectionable drying out and loss of flavor heretofore experienced is quite eliminated.

The primary object of the invention is thus substantially to house the cigarettes and at the same time permit them to be dispensed individually as required. With this object in view, I have provided means within the channel 14 cooperating with the gate 28 for delivering a single cigarette from the magazine to the gate each time the gate is opened. This means, as illustrated, comprises a pair of selector elements 34 on a shaft 35, the elements extending upwardly into the magazine and the ends of the shaft being supported respectively in the left side wall of the member 10 and extending through an opening in the right side wall thereof so closely as fully to close such opening. Aligned recesses 36 are formed in the peripheries of the elements of a size to receive a cigarette thereinto and the selector is rotatable to and between the two extreme positions shown in Figs. 4 and 5. In the normal position (Fig. 4), the cigarettes at the extreme bottom of the magazine are supported on the peripheries of the elements 34 and a cigarette has been delivered to the gate. In the dispensing position, the recesses 36 have been brought to the magazine and a cigarette has dropped thereinto.

Each time the gate is opened to dispense a cigarette 37 (Fig. 5), the selector must be rotated to deliver another cigarette from the magazine thereto and, to this end, the gate and selector are connected for simultaneous and synchronous operation. The right-hand side wall is preferably recessed at 38 and housed within this recess are connections between the gate and shaft, comprising a gear segment 40 on the gate pivot in mesh with a pinion 42 on the shaft. A spring 43 holds the parts in the normal position (Fig. 4) and the recess may be closed by a plate 44. The gate and connected parts are operated by an arm 45 secured to the gate pivot outside of the plate.

The cigarettes are normally completely enclosed, as illustrated in Fig. 4, and when a cigarette is desired the arm 45 is depressed. This operation brings the gate to the position of Fig. 5, whereupon the cigarette 37 rolls off the gate and down the inclined supports 46 and into the depressions 47. These supports may be formed integral with the member 10 and they may be recessed to provide a pair of stops 48 for the gate. Through the connections above described, the selector is also rotated to the position of Fig. 5, whereupon a cigarette drops into the recesses 36 and is delivered to the gate, when it again closes. It will, therefore, be seen that a single cigarette is dispensed each time the gate is opened and that the cigarettes within the dispenser are otherwise completely housed from exposure to the atmosphere.

It is pointed out that rotation of the elements 34 serve the additional function of rotatably agitating the cigarettes in contact therewith, thereby causing one to drop freely into the recesses 36.

The elements 34, therefore, form an agitator-selector which performs two functions. Attention may also be directed to the relative spacing of the supports 46, whereby the intermediate portion of the dispensed cigarettes 37 is left free to be conveniently grasped by the fingers. Various refinements may be provided on the dispensed as, for example, a pad 50 on the under side of the cover for receiving perfume, menthol, moisture or the like, with which to treat the cigarettes, and the exterior of the walls may be ornamented as illustrated or otherwise.

In Fig. 6, I have illustrated a somewhat modified form of dispenser and how it may be combined with such other pieces as smoker's stands, ash trays, desk sets, etc. The top or upper wall of such a piece is indicated at 52 and the dispenser 53 may be mounted thereon as by means of one or more pegs 54 projecting from the dispenser and engaging within corresponding holes in the wall. A cigarette-receiving depression 55 is provided in the wall forwardly of the dispenser.

In Figs. 7-9, I have illustrated another modified form of the dispenser adapted to be mounted within a smoker's cabinet. The front and top walls of the cabinet are indicated by reference characters 56 and 58. The shape of the dispenser is somewhat different from that shown in Figs. 1-5 but the general construction and operation are the same. The body member 60 is adapted to be mounted within the cabinet with its front wall in contact with the inner surface of the wall 56 and it may be removably supported therein by a bracket 61 and spring clips 62, the latter engaging shoulders 64 formed on the side walls of the 35 dispenser. The gate 65 and selector 66 are operated by connected racks 67 and 68 in mesh with pinions 69 and 70. A spring 72 holds the racks in the outermost position and in such position the gate is tightly closed. Cooperating with the racks 40 is a forwardly-projecting bar 71 and the lowermost portion of the dispenser is constructed in the form of a cigarette-receiving shelf 72. When the dispenser is mounted within the cabinet, as illustrated, the lowermost portion thereof extends 45 through an opening 73 in the wall 56 and the bar 71 also extends through an opening thereabove.

The clips 62 permit ready removal and replacement of the dispenser for reloading purposes and the cigarettes are normally housed within both 50 the dispenser and the cabinet. When a cigarette is desired, the operator pushes the bar or button 71 inwardly, which thereupon opens the gate 65 and dispenses the cigarette 74 and at the same time operates the selector to deliver a cigarette 55 from the magazine to the gate, all as heretofore described in connection with Figs. 1-5. The dispensed cigarette rolls to the shelf 72, from which it can be conveniently grasped.

In Figs. 10-14, I have illustrated the adaptation of my invention to the dispensing of cigarettes from the original container in which they are purchased, thus eliminating any handling thereof prior to their use. In this case, the cigarettes are packed and sold in a container or box 65 75 of any suitable material, such as metal, waterproof paper or the like. A cover 76, in conjunction with a filler 77, serves to protect the cigarettes and hold them compactly within the box during storage and transportation.

The dispenser which is adapted to receive the container 75 is illustrated in Fig. 11 and comprises a body member 78 equipped with a selector 79, a gate 80, inclined supports 81 and an operating arm 82, all in like manner as the dispenser shown 75

in Figs. 1-5. The upper open end 84 of the dispenser is shaped to receive closely the open end of the container 75 after the cover 76 and filler 77 have been removed and a resilient gasket 85 is provided for receiving and forming a sealing contact with the top edge of the container. The dispenser is also provided with a pair of resilient arms 86 molded thereinto and having their free ends diverging outwardly. The intermediate portion of the arms are formed into detents 87 for engaging within openings 88 formed in the container to hold the same in tight contact with the gasket 85, as hereinafter described. The detents 87 are normally in position to engage with 15 in the openings 88 and the member 78 is recessed at 89 rearwardly of the detents to permit the arms to be swung rearwardly when the container is being inserted or removed. The openings 88 in the end walls of the box 75 are in position to be closed by the cover 76 and the detents 87 are 20 of a size substantially filling these openings, as shown in Figs. 10 and 12.

The dispenser 78 is reloaded as follows. The cover 76 and filler 77 are removed from the box 25 and the dispenser in inverted position (Fig. 14) is placed thereover in lieu of the cover. This operation is facilitated by the arms 86, which serve to guide the box into the opening, and when the box is fully inserted, with its edge in tight contact with the gasket 85, the detents 87 will snap into the openings 88 and hold the box in such position. Thus the dispenser has been substituted for the cover 76. The combined dispenser and box are now turned to the upright position and the box becomes the magazine for the dispenser, the box being closed to a condition substantially as tight as when the cover 76 was in place thereon.

In order further to protect the cigarettes and give the dispenser a pleasing appearance, I mount 40 a hood 90 over the inverted box. This hood is of a size closely receiving the box and is grooved at 91 to receive the arms 86. When placing the hood, the arms are pressed tightly against the box and the hood slid thereover to the full position shown in Figs. 10 and 12. It will be apparent that the hood cannot be placed to this position if the detents 87 are not fully engaged within the openings 88, thus insuring that the box is in full position against the gasket 85. It will also be apparent that the natural outward resiliency of the arms serves to hold the hood in the position shown in Figs. 10 and 12.

The parts are shown in the fully assembled relation in Figs. 10 and 12 and in such relation the cigarettes are tightly enclosed within the box, which thereupon serves as a magazine for the dispenser. The cigarettes are dispensed by operating the arm 82 in the same manner as heretofore described in connection with Figs. 1-5.

It will be understood that the dispenser and magazine box and the cooperating elements therebetween may be considerably modified within the scope of the invention. For example, as 65 illustrated in Fig. 15, the box 93 may have depressions or recesses 94 formed in the end walls thereof and the dispenser 95 may have arms 96 provided with lugs 97 adapted to be engaged within such depressions. The arms 96 normally 70 diverge outwardly in a manner serving to guide the box into the dispenser and the lugs 97 are normally spaced from the box. The dispenser and box are assembled by inverting the dispenser over the box, as illustrated in Fig. 14, and when 75 the assembled elements are turned to the upright

position the arms are pressed against the sides of the box with the lugs engaged within the depressions while the hood 98 is inserted thereover, the hood being recessed at 99 to receive the arms. When the box and hood are in full position on the 5 dispenser, the hood holds the lugs engaged within the depressions and the resiliency of the arms serve to retain the hood in place.

Having thus described my invention, what I claim as new and desire to secure by Letters 10 Patent is:

1. A cigarette dispenser comprising the combination of a body member having a downwardly-extending channel therethrough open at its ends and adapted to permit the passage of cigarettes laterally, a separate cigarette container having an opening permitting the lateral passage of cigarettes therefrom, means so adapting the container to the member that said opening may be placed adjacent to and in alignment with the upper end of the channel in position to supply cigarettes to the channel, inter-engaging means comprising recesses formed in the container walls and cooperating detents carried by the member for locating and holding the container in said position, a pivotally-mounted gate for dispensing cigarettes from an opening at the bottom end of the channel, said gate normally closing the opening in a substantially air-tight manner, and means in the body member cooperating with the gate for dispensing a single cigarette when the gate is opened.

2. The combination of claim 1, including arms carrying said detents and having their lower ends secured to the body member and their free ends diverging outwardly to receive and guide the container therebetween.

3. The combination of claim 1 plus arms carrying said detents and having their lower ends secured to the body member, and a hood for covering the container and having the inner walls thereof so spaced as to receive the arms and container thereinto only when the detents extend into said recesses.

4. A cigarette dispenser comprising the combination of a body member having an upper portion providing a cigarette magazine and a relatively restricted lower portion providing a downwardly-extending channel leading from the bottom of the magazine, a cigarette selector rotatably mounted in the channel and having a cigarette receiving recess therein, the selector forming a portion of the bottom of the magazine wider than the recess, a gate pivoted to the member and closing the bottom end of the channel against the passage of air by contact around the periphery thereof in the closed position, means normally holding the gate in closed position, and connections between the gate and selector whereby they operate simultaneously and the selector delivers a cigarette in its said recess from the magazine to the bottom end of the channel each time the gate is operated in one direction and a cigarette is dispensed from the bottom end of the channel each time the gate is opened.

5. A cigarette dispenser comprising the combination of a body member having a downwardly-extending channel therethrough open at its ends and adapted to permit the passage of cigarettes laterally, a separate and removable container adapted to hold a supply of cigarettes prominently therein and having an opening permitting the lateral passage of the cigarettes therefrom, the container and member being so constructed that the former may be applied to the 75

- latter in position thereon to supply cigarettes from said opening to the upper end of the channel while forming a substantial closure preventing the passage of air into and from the channel, 5 a gate for tightly closing the bottom end of the channel, means normally holding the gate in closed position, rotary selecting means in the channel having a peripheral portion thereof forming a bottom support for the said cigarettes 10 and acting when rotated to rotatably agitate the cigarettes resting thereagainst, said selecting means having a recess within said peripheral portion adapted to receive a cigarette from said upper end of the channel, connections between the selecting means and gate whereby said means rotates in a direction bringing said recess to the 15 said upper end of the channel when the gate moves in one direction and rotates in the opposite direction bringing a cigarette therein to the bottom end of the channel when the gate moves 20 in the other direction, and a removable hood complementary to the body member fitting over and covering the container.
6. A cigarette dispenser comprising the combination of a body member having a downwardly extending channel therethrough for the passage 25 of cigarettes laterally, a cigarette magazine on the member in communication with the top end of the channel, a gate substantially closing the bottom end of the channel against the passage 30 of air by contact around the periphery thereof

in the closed position, means normally holding the gate in closed position, a recessed agitator-selector in the channel and forming a portion of the bottom wall of the magazine, and connections therefrom to the gate whereby the agitator-selector is moved in a manner agitating the cigarettes in the magazine and causing its recessed portion to deliver a single cigarette from the magazine to the gate at each dispensing operation of the gate, the side walls of the channel being closed whereby to prevent passage of air therethrough to the channel. 10

7. A cigarette dispenser comprising the combination of a body member having a downwardly extending channel therethrough for the passage 15 of cigarettes laterally, a cigarette magazine on the member in communication with the top end of the channel, a pivotally movable gate substantially closing the bottom end of the channel against the passage of air by contact around the periphery thereof in the closed position, means normally holding the gate in closed position, a recessed selector rotatably mounted in the channel and forming a portion of the bottom wall of the magazine, and connections between the selector and gate whereby they operate simultaneously and the recessed portion of the selector delivers a cigarette from the magazine to the bottom end of the channel at each dispensing 20 operation of the gate. 25

LAWRIE L. WITTER. 30
